UNITED STATES PATENT OFFICE

EDWARD R. HEWITT, OF MIDVALE, NEW JERSEY, ASSIGNOR TO INTERNATIONAL MOTOR COMPANY, OF NEW YORK, N. Y., A CORPORATION OF DELAWARE

SOLID-INJECTION OTTO-CYCLE ENGINE

Application filed June 28, 1927. Serial No. 202,058.

Internal combustion engines in general use are provided with fuel, usually, by means of a carburetor which vaporizes the liquid fuel and mixes it in desired proportions with sufficient air to support combustion, the mixture being conducted to the intake manifold through suitable conduits. During the entire life of this form of fuel supply, no device has been constructed which can vaporize and form a mixture which is free from particles of liquid fuel or which produces a mixture, every portion of which has a desired uniform air and vapor content.

Recognizing the desirability of reaching, as far as possible, the most favorable condition wherein the completely vaporized fuel is mixed with air to form a uniform and homogeneous fluid; and realizing that the carburetor, alone, is unable to form a mixture of this character at all times, the trend of development, in recent years, has been with auxiliary devices, such as heaters, agitators, etc. to aid in forming a perfect mixture. Additional designs employ an impact mechanism to exert a sudden and powerful blow upon a fluid column, an injector constraining the flow of the column and injecting the fuel into the combustion space.

It is with this last form of device that the present invention deals, an object being to utilize an impact mechanism to produce a spray which is carried by the air current to the combustion space to be ignited.

More particularly, an object of the invention is to provide a means for producing an intimate mixture of fuel and air by spraying into the intake air current, a finely atomized amount of fuel periodically to be carried by the air into the combustion space, the paths of the air and fuel being such that the direction of flow of one will be reversed by the other, or both be changed, the turbulence resulting from such condition aiding materially in perfecting the mixture.

Other and further objects will appear as the description proceeds and reference will now be had to the accompanying drawings for a more detailed description of the invention, wherein:

Figure 1 is a sectional elevation showing

one form of the invention, the section being taken on line 1—1 of Figure 2.

Figure 2 is a sectional view taken on line 2—2 of Figure 1 and looking in the direction of the arrows.

Figure 3 is a sectional view of a modified form of the invention.

Referring particularly to Figures 1 and 2, *a* designates the engine block with a head *b*, both being of common form and no part of the present invention. The block is formed with intake and exhaust ports *c* and *d*, respectively, valves *e* controlling the flow of gases to and from the engine. A cylinder *f* contains the usual piston *g* and above the piston and in the head is a combustion chamber *h*. The combustion chamber *h* is provided with the usual spark plug *i* and above the intake valve is an injector *j* of the impact type, as disclosed in my copending application for Letters Patent, Serial No. 202,061, filed on even date herewith. This injector is centered over the intake valve and is constructed to throw a conical spray of vapor over the intake valve at its edges as shown in dash lines in Figure 2.

The arrows represent the flow of the intake air and it will be apparent that it will pass up and around the valve, filling the combustion chamber and flowing into the cylinder. As the air flows upwardly, it will be met by a conical spray of fuel vapor and the turbulence resulting from the collision of these two currents aids, materially, in forming a uniform mixture. As shown the paths of the air and fuel intersect at approximately right angles.

By reason of introducing the fuel directly at the combustion space, the pipes and fittings do not become traps for the heavy ends of fuel and impurities and the system may thus be maintained clean with little difficulty. A further and greater advantage of this construction is that the volumetric efficiency is increased since the air can be taken directly from the atmosphere and needs no pre-heating. An additional result flowing from this condition is an increase of power output by reason of relieving the engine of the necessity of maintaining the vacuum required to draw

the mixture through the carbureter, the added power output being between ten and fifteen percent of the total power available.

In Figure 3, the relation of parts is reversed, the valve being of the overhead type and the injector being positioned below the valve so that its spray is projected into the path of the gases. In this case the intersecting paths promote the intimacy of the mixture.

It is apparent that the specific form of the invention may be changed and the parts arranged in a different manner and the invention is not to be limited save as defined in the appended claims.

What I claim is:

1. In an internal combustion engine, a cylinder, an intake valve, means to introduce a supply of air into the cylinder through the valve, and means centered over the intake valve to exert an impact on fuel to inject it into the engine, means to direct the fuel in a conical spray over the edges of the valve to strike the upward current of air therethrough, whereby an intimate mixture of air and fuel will result.

2. Method of introducing fuel into an internal combustion engine comprising exerting an impact force on the fuel, directing the fuel in a conical spray whose perimeter at the air inlet valve approximately coincides therewith, and simultaneously admitting air through said valve.

This specification signed this 16th day of June, A. D. 1927.

EDWARD R. HEWITT.
